UNITED STATES PATENT OFFICE

WESTERN UNDERWOOD, OF SANTA MONICA, CALIFORNIA, ASSIGNOR TO LA LUX MANUFACTURING COMPANY, OF LOS ANGELES, CALIFORNIA, A CORPORATION OF CALIFORNIA.

INSERT FOR MOLDS

Application filed December 14, 1927. Serial No. 239,915.

This invention has to do with an insert for a mold and has particular reference to an insert for a post or column mold.

Elongated monolithic or cementitious objects, such for example as columns or posts, are usually cast or formed in suitable molds and in accordance with various processes of manufacture, the molds are operated in various ways to obtain the desired packing of the material. In certain cases, for instance in the case of a post to be used in a lighting standard or electrolier, it is desirable to provide a longitudinal opening through the cast body and it is ordinarily necessary to provide a metal reinforcing structure in the cast body. In practice, difficulty has been experienced in obtaining the desired opening through a post or column and also in forming a post with a metal reinforcement under proper conditions of strain and in the proper position in the cast body.

An object of this invention is to provide a mold insert whereby the molded product or post is provided with an effective reinforcing structure under conditions to assure a proper bond between the structure and cast material and in a definite predetermined position in the cast material. The insert provided by this invention facilitates the casting of a reinforcing structure in a post, or the like, without putting the structure under strains, such as tends to break the bond between the structure and cast material when the post is removed from the mold.

35 A further object of the invention is to provide a simple, improved reinforcement for insertion in a post mold to be cast in the finished post.

40 It is another object of this invention to provide a spacer whereby a reinforcing structure is definitely and accurately spaced or positioned in a mold without being put under tension or otherwise strained.

45 The various objects and features of this invention will be understood from the following detailed description of the invention, throughout which description I refer to the accompanying drawings, in which:

50 Fig. 1 is a longitudinal detailed sectional

view of a post mold showing the insert provided by this invention in place therein;

Fig. 2 is a view of the base end portion of the insert shown independent of the mold;

Fig. 3 is a view taken as indicated by line 55 3—3 on Fig. 2 showing the formation of the core carrier;

Fig. 4 is an enlarged transverse sectional view taken as indicated by line 4—4 on Fig. 1, being a view showing in detail the spacer 60 provided by my invention; and

Fig. 5 is a sectional view taken as indicated by line 5—5 on Fig. 4.

The insert provided by this invention is intended primarily for use in a mold, such, for instance, as a post mold, or the like. For purpose of example, I will refer to the insert as applied to a post mold of the construction set forth and claimed in my co-pending application, entitled "Mold construction", 70 filed on even date herewith. This particular mold includes an elongated sectional body 10, having an opening A designed or shaped to give the post the desired external configuration. The body 10 is different at its two ends, one end being comparatively large to form the base portion of the post, the other end being small and adapted to form the head end of the post. The head end of the body 10 is closed by a cover plate 11 over which is applied mounting plate 12, while the base end of the body is closed by the core carrier 12 provided by this invention and a mounting plate 13 applied over the core carrier.

75 The insert provided by this invention includes, generally, an elongated core 14 to be arranged longitudinally through the opening A in the body, the core carrier 12 which is applied to the base end of the body and supports the core 14, a reinforcement 15 for arrangement in the space A to be cast in the post, and a spacer 16 operable to definitely space the reinforcement in the post. The reinforcement 15 and spacer 16 are claimed in this application, the core 14 and carrier 12 being set forth and claimed in my divisional application entitled Core for molds, Serial No. 437,995, filed March 22, 1930.

80 85 90 95 100 The core 14 is shaped and proportioned to form the desired opening in the cast struc-

ture or post, and in the case of a post for the usual form of lighting standard, the core is provided with an enlarged base part 20 which forms a comparatively large chamber in the 5 base portion of the post, and an elongated body part 21 which is slightly tapered and extends from the base part 20 to the head end of the mold. The body part 21 of the core has its large end adjoining the base 20 and 10 the base is provided with a taper or draft allowing the core to be withdrawn from the molded post from the base end. In the preferred construction, the core is formed of metal, for instance sheet metal, and in this 15 case the core parts are hollow. In accordance with my invention, a plug 22 closes the small or outer end portion of the core body 21 as shown in the drawings. The plug is preferably somewhat removed from the end of the 20 body so that a socket B is formed in the end of the core body to receive a guide part on the mold cover 11 and/or various tools or devices as set forth in my above-mentioned co-pending application. The plug is fixed in the core 25 body so that it can be engaged in driving or forcing the core out of the casting. In Fig. 1 of the drawings, the core is shown in position where a projection on the cover 11 extends into the socket B to hold the core 30 body in position in the opening A.

The core carrier 12 is preferably in the form of a flat plate adapted to be attached to the base end of the mold body 10, as shown in Fig. 1. The carrier 12 is adapted to be 35 mounted in a definite position on the base through bolts 25, or the like. In accordance with this invention, the base portion 20 of the core is attached to the carrier 12, preferably permanently attached. I provide one or 40 more openings 26 in the core carrying plate 12, through which the material to be cast can be filled into the mold. In the drawings, I have shown a construction wherein there are several openings 26 which communicate with 45 the opening A in the body of the mold when the core carrier 12 is in place, as shown in Fig. 1. Further, the opening or openings 26 in the core carrier are located to be closed by the mounting plate 13 upon the mounting plate 50 being arranged in place, as shown in Fig. 1.

The core structure that I have provided is not only a particularly simple and an inexpensive structure, but is also very convenient to handle. It is to be noted that the core, 55 when in place, is effectively supported at both ends so that it is positively held in a predetermined position in the space A in the mold body. Further, as above pointed out, my construction allows the mold to be filled 60 with the core set in position and permits of the core being withdrawn from the cast body without disturbing the casting in the mold body 10.

The reinforcement 15 provided by my invention includes, generally, a plurality of

longitudinal rods 28, foot brackets 29 on the lower or base ends of the rods, and one or more transverse ties 30 extending between the rods. The rods 28 may be formed of suitable reinforcing bars such as are used in reinforcing concrete structures, and the like, it being preferred to use twisted, square bars or the equivalent. In practice, I may use any desired number of bars 28, it being understood that the number and weight of bars will depend on the character of reinforcement desired. The foot brackets 29 are fixed, for instance, welded, or otherwise positively secured, to the base ends of the rods 28, and are formed to have projecting parts 31 adapted to be attached to the base end of the mold body 10. The upper or head ends of the bars 28 preferably project from the finished post and therefore are proportioned to project into suitable sockets or openings provided in the cover plate 11 of the mold body. My construction is such that the head ends of the rods 28 do not have to be made tight in the cover 11 of the mold, in fact, it is preferred that they be allowed to extend freely into the openings of cover 11 so that the cover merely operates to space them apart and not hold them longitudinally. The transverse tie or ties 30 may be in the nature of wires wound around the several rods 28 in a manner such as I have illustrated in the drawings. The tie 30, when properly applied to the rods 28, ties them in or together so that they have little or no tendency to expand or move out radially in the event the mold structure in 100 which the reinforcement is spaced is rotated in the course of manufacture of the post.

The spacer 16 provided by my invention is in the nature of a ring or annular member adapted to engage the several rods 28 and to 105 surround the body 21 of the core so that it operates to definitely hold and space the rods 28 with reference to the core and therefore in the space A of the mold body 10. My invention provides a ring 32 adapted to fit 110 around the core body 21 with substantial clearance and made comparatively narrow or thin so that it occupies comparatively little space in a radial direction in the mold space A. In accordance with my invention, the ring 32 is provided with a plurality of inwardly extending lugs 33 adapted to engage the core body 21 so that the ring 32 is definitely, for instance, concentrically, related to 115 the core body. Further, my invention provides a plurality of outwardly projecting lugs 34 on the ring 32, the lugs 34 being provided to hold the bars 28 of the reinforcement. In the preferred construction, the lugs or projection 34 are provided with openings 120 to pass the bars 28 as clearly shown in Fig. 4 of the drawings. In the drawings, I have disclosed an arrangement wherein there is a single spacing ring embodied in the structure or mold insert. It is to be understood, how- 125

ever, that any desired number of spacing rings may be provided as circumstances may require.

From the foregoing description, it will be apparent that my invention provides a structure or combination of parts for insertion of a mold body whereby the cast structure is cored to have an opening in a definite position, and whereby a suitable reinforcing structure is embodied in the casting in a definite position without requiring tensioning or other straining, such as is liable to interfere with the proper bond between the reinforcement and cast material.

Having described only a typical preferred form of my invention, I do not wish to limit myself to the specific details set forth, but wish to reserve to myself any changes or variations that may appear to those skilled in the art or fall within the scope of the following claims.

Having described my invention, I claim:

1. An insert for a post mold including, a plurality of longitudinal rods, foot brackets fixed to the base ends of the rods, ties connecting the rods, and a ring having openings holding the rods in definite spaced relation intermediate their ends, the ring having spaced projecting lugs with openings to pass the rods.

2. An insert for a post mold including, a plurality of longitudinal rods, foot brackets fixed to the base ends of the rods, ties connecting the rods, and a ring having openings holding the rods in definite spaced relation intermediate their ends, the ring having spaced inwardly projecting lugs and spaced outwardly projecting lugs, the outwardly projecting lugs being provided with openings to hold the rods.

In witness that I claim the foregoing I have hereunto subscribed my name this 6th day of December, 1927.
